CLAIM

The ornamental design for an effervescent tablet for bath water, as shown and described.

DESCRIPTION

FIG. 1 is a perspective view of an effervescent tablet for bath water showing my new design;

FIG. 2 is a top plan view thereof;

FIG. 3 is a right side elevational view thereof;

FIG. 4 is a bottom plan view thereof;

FIG. 5 is a front elevational view thereof;

FIG. 6 is a rear elevational view thereof;

FIG. 7 is a perspective view of a second modified embodiment;

FIG. 8 is a top plan view thereof;

FIG. 9 is a right side elevational view thereof;

FIG. 10 is a bottom plan view thereof;

FIG. 11 is a front elevational view thereof; and,

FIG. 12 is a rear elevational view thereof.

The stippling represents a roughened surface.
